(57) **CLAIM**

We claim the ornamental design for a fitting, as shown and described.

DESCRIPTION

FIG. 1 is a front perspective view of the fitting in its environment with a pipe inserted in one end;
 FIG. 2 is a front and top perspective view of the fitting;
 FIG. 3 is a side view of the design shown in FIG. 2;
 FIG. 4 is a top view of the design shown in FIG. 2;
 FIG. 5 is a bottom view of the design shown in FIG. 2; and,
 FIG. 6 is a cross sectional view of the design shown in FIG. 1 taken along line 6 and shown in use with a pipe having been inserted in each end.

The broken lines shown in the drawings illustrate environmental subject matter only that form no part of the claim.
